(57) **CLAIM**

The ornamental design for a display screen or portion thereof with graphical user interface, as shown and described.

DESCRIPTION

FIG. 1 is a first image of a display screen or portion thereof with graphical user interface in accordance with the present invention;

FIG. 2 is a second image of the display screen or portion thereof with graphical user interface in accordance with the present invention;

FIG. 3 is a third image of the display screen or portion thereof with graphical user interface in accordance with the present invention;

FIG. 4 is a fourth image of the display screen or portion thereof with graphical user interface in accordance with the present invention;

FIG. 5 is a fifth image of the display screen or portion thereof with graphical user interface in accordance with the present invention;

FIG. 6 is a sixth image of the display screen or portion thereof with graphical user interface in accordance with the present invention;

FIG. 7 is a seventh image of the display screen or portion thereof with graphical user interface in accordance with the present invention;

FIG. 8 is an eighth image of the display screen or portion thereof with graphical user interface in accordance with the present invention;

FIG. 9 is a ninth image of the display screen or portion thereof with graphical user interface in accordance with the present invention;

FIG. 10 is a tenth image of the display screen or portion thereof with graphical user interface in accordance with the present invention;

FIG. 11 is an eleventh image of the display screen or portion thereof with graphical user interface in accordance with the present invention; and,

FIG. 12 is a twelfth image of the display screen or portion thereof with graphical user interface in accordance with the present invention.

The outermost broken lines depicting a monitor and the display screen form no part of the claimed design. The remaining broken lines depict portions of the graphical user interface that form no part of the claimed design.

The appearance of the display screen or portion thereof with graphical user interface sequentially transitions between the
